UNITED STATES PATENT OFFICE.

JOHN L. MALM, OF DENVER, COLORADO, ASSIGNOR TO THE MIDWEST METALS COMPANY, OF DENVER, COLORADO, A CORPORATION OF COLORADO.

BARREL.

1,255,196.

Specification of Letters Patent.

Patented Feb. 5, 1918.

Application filed April 26, 1915. Serial No. 24,015.

To all whom it may concern:

Be it known that I, JOHN L. MALM, a citizen of the United States, residing at Denver, in the county of Denver and State of Colorado, have invented certain new and useful Improvements in Barrels, of which the following is a specification.

This invention relates generally to barrels and particularly to that class of such devices used for filtration and agitation purposes.

More specifically the invention relates to an agitating barrel rotatably mounted and provided on its periphery with suitable charging and dumping doors arranged on one longitudinal line, together with longitudinally disposed baffles arranged on the inner wall and cut at suitable points by spirally arranged baffles which converge toward the doors to bring about the collection and concentration of the mass toward the doors to facilitate the discharging operation, the direction of rotation of the barrel being such that this collection or concentration is brought about by these converging baffles.

The invention also relates to the arrangement of foraminous, fibrous material on the inner wall between the baffles for supporting a suitable filtering medium or cloth, the object of utilizing the fibrous material being to provide a chamber or space for the collection of the liquor passing through the filtering medium, the liquor being collected from this chamber in any suitable manner.

The invention is an improvement upon the structure illustrated and described in my patent for barrels, No. 1,215,565, granted February 13, 1917.

The invention may be further briefly summarized as consisting in the construction and combination of parts hereinafter set forth in the following description, drawings and claims.

Referring to the drawings, Figure 1 is a view partly in elevation and partly in vertical section showing the device; Fig. 2 is a horizontal section looking upward toward the discharge doors; Fig. 3 is a section upon the line 3—3 of Fig. 1; and Fig. 4 is a section upon the line 4—4.

In carrying out the invention any preferred type of barrel may be employed so long as it possesses the necessary characteristics, but I have shown one embodiment which is effective, and it will now be described.

Supported on any suitable masonry set-

ting are bearings 1 and 2 which receive hollow trunnions 3 and 4 respectively, the former preferably forming a part of a barrel head 5 and having at its outer end a suitable gas or fluid pressure connection 6, the other hollow trunnion 4 forming a part of a barrel head 7, and within the bearing 2 provided with openings 8 through the wall for a purpose to be described. Each of the trunnions 65 is provided with an inwardly extending flange 9, and these flanges receive the barrel casing in this instance made up of staves or boards 10 braced and held throughout the length by suitable straps 11. The heads are 70 held against endwise displacement by suitable rods 12 secured in the heads in any obvious manner, no connection of the heads being shown, however, but the arrangement being one which is ordinarily employed in 75 such construction.

On one longitudinal line in the periphery or shell, suitable openings 13 are provided, and these openings provide access to the barrel. Each of the openings 13 is closed by a 80 suitable door construction, and each comprises a cast door 14 pivotally mounted upon a bar 15 in turn pivotally connected to a pair of links 16, these links being in turn pivotally connected to suitable ears formed on a 85 ring 17 connected to suitable straps 18 passing around the barrel. The other end of the bar 15 is provided with an open-ended slot 19 extending inward from the end, and this slot receives a bolt 20 having an eye 21 engaging a pin 22 carried by the ring 17. A suitable nut 23 engages the threaded shank of this bolt and serves as a means for holding the bar in position with the door closed. The door 14 is provided with a suitable lining 24 fitting nicely into the opening 13 in 90 the shell.

The staves or boards 10 forming the shell or casing are notched near each end to form internal annular grooves 25 and the groove 100 corresponding to the head 7 receives a suitable head lining 26 which is spaced from the head by suitable spacing strips 27. This head closes the opening in the hollow trunnion 4. At the opposite end the groove 25 receives a suitable head lining 28, preferably of boards, and having at the center a suitable opening 29 registering with the opening in a tubular extension 30 forming a part of the head 5, thus serving to furnish communication between the gas and fluid pressure inlet 6 and the inside of the barrel.

Secured to the inner wall of the barrel, extending longitudinally thereof and spaced around the periphery are pairs of strips or cleats 31. These strips are spaced from each other and they receive between them the folded portion 32 of a filter cloth or medium 33, the folds 32 being held between the cleats 31 by baffle strips 34 wedged into the notch formed by the fold, as is clearly shown in Figs. 3 and 4. These baffle strips 34 extend inward for a short distance and serve to agitate the material which is in the barrel when it is rotated. Between adjacent pairs of strips or cleats 31 are mats or plates 35 of fibrous material, such as cocoa matting, and these mats or strips serve to hold the filter cloth or medium away from the internal periphery of the shell or casing and thereby form chambers for receiving the liquor filtering through the filter medium. These chambers are drained by ports 36 extending radially through the wall and communicating at various points throughout the length of the barrel with a discharge manifold pipe 37. This pipe 37 at the right end of the barrel, as shown in Fig. 1, or at the end corresponding to the head 7 extends to the center through one of the openings 8 into the opening of the hollow trunnion 4. There is a manifold discharge pipe for each of the longitudinal chambers formed by the baffles 34, and these several pipes pass through the opening in the hollow trunnion 4 to any suitable point where the liquor may be collected therefrom.

It will be seen from the foregoing construction that after the material is charged into the barrel and the doors are closed, pressure is supplied through the connection 6 and the barrel is set in motion, with the result that the material is agitated and at the same time the fluid pressure serves to drive the liquor from the material through the filter medium into the chambers formed by the cocoa matting, from whence the liquor passes through the discharge manifolds out through the hollow trunnion 4. This agitating and filtering operation is conducted for the proper length of time and after it is completed and all of the liquor has been withdrawn, pressure is supplied to the discharge manifold pipes 37, and the cake, which has collected upon the inside of the filtering medium, is released or loosened up from the filter cloth or medium. The apparatus is then ready to be charged.

In order to facilitate the discharge of the material through the openings 13, I provide collecting or concentrating baffles 38 which extend spirally in two directions toward the doors, as shown in Fig. 2. These baffles cut the longitudinally disposed baffles and they serve to cause the material to collect and

concentrate toward the doors and to pass out as the doors move toward the bottom in 65 the rotation of the barrel. In this way the cake loosened from the filter cloth or medium is quickly discharged from the barrel. After operation and after the material has been discharged, the wet filter cloths hang 70 loosely from the cocoa matting, as shown in Figs. 3 and 4.

Having described my invention, I claim:

1. An agitating barrel, comprising a hollow cylindrical body closed at one end and provided at its opposite end with communication to a source of fluid pressure, the inner surface of said body being provided with a series of longitudinally extending baffles, a door in the wall of said body intermediate its ends, and additional baffles converging spirally in both directions from the ends of the body toward said door and intersecting the longitudinally disposed baffles, said spirally arranged baffles being adapted to collect the material and facilitate its discharge through the door.

2. An agitating barrel, comprising a hollow cylindrical body closed at one end and provided at its opposite end with communication to a source of fluid pressure, the inner surface of said body being provided with a series of longitudinally extending baffles, filter sheets on the inner wall of said body 95 extending from baffle to baffle and supported thereby and forming with the inner surface of the wall of the body a series of filtrate receiving chambers, means for conducting the filtrate from said chambers, a door in the 100 wall of said body, additional baffles converging spirally in both directions from the ends of said body toward said door, said spiral baffles being adapted to collect the filtered material and facilitate its discharge through 105 the door when the body is rotated.

3. An agitating barrel, comprising a hollow cylindrical body closed at one end and at its opposite end provided with communication to a source of fluid pressure, the inner surface of said body being provided with a series of longitudinally extending baffles, a plurality of doors in the wall of said body, and sets of converging spirally arranged 110 baffles on the inner surface of the body wall, one set for each door, said spirally arranged baffles being adapted to direct the material toward said doors and facilitate its discharge therethrough.

In testimony whereof I affix my signature 120 in presence of two witnesses as follows.

JOHN L. MALM.
